UNITED STATES PATENT OFFICE.

CARTER D. STAMPER, OF BEATTYVILLE, KENTUCKY.

REGISTERING SEAL-PRESS.

1,028,914.

Specification of Letters Patent. Patented June 11, 1912.

Application filed June 21, 1910. Serial No. 568,095.

To all whom it may concern:

Be it known that I, CARTER D. STAMPER, a citizen of the United States, and a resident of Beattyville, in the county of Lee ⁵ and State of Kentucky, have invented a new and Improved Registering Seal-Press, of which the following is a full, clear, and exact description.

The invention has in view a press having ¹⁰ associated therewith a register to indicate the number of impressions taken, the press and register being so combined as to secure simplicity of construction and insure the positive operation of the register, access to ¹⁵ the latter being had only by the removal of a closure, ordinarily in the nature of a hinged door, which door is normally locked and sealed, and is to be opened only by the proper officer.

²⁰ The registering press is particularly designed for the seals of States. It is the practice in some of the States of the United States to furnish a seal press to each of its counties and make a prescribed charge for ²⁵ each impression taken. At present there is no way of checking on the officer having the press in charge. With my improved press, the State auditor or other proper officer keeps the key to the door affording ³⁰ access to the register, and in auditing or examining the accounts of the county clerk or other officer having the press in charge, takes the reading of the press register and, if desired, opens the door by unlocking it ³⁵ and breaking the seal, and turns the register back to zero, the door being again locked and sealed.

⁴⁰ Reference is to be had to the accompanying drawings forming a part of this specification, in which similar characters of reference indicate corresponding parts in all the views.

Figure 1 is a longitudinal vertical section through a registering seal press constructed ⁴⁵ in accordance with my invention; Fig. 2 is a plan of the same, with the operating lever removed; and Fig. 3 is a perspective view of the press and register plungers.

The press is constructed after the general ⁵⁰ form of the conventional seal or embossing press, comprising the seating base 5, to the rear end of which is rigidly connected the overhanging arm 6, in which the press plunger 7 is vertically slidable, the base 5 and ⁵⁵ the plunger 7 carrying the usual seal or embossing dies 8 and 9 respectively.

In accordance with my invention, the overhanging arm 6 is recessed at one side adjacent to the plunger 7, to receive a register 10, the latter being plunger-actuated and otherwise of the usual or other preferred construction, and having the customary opening 11, through which the register is readable. The recess in which the register is normally located is closed by a suitable ⁶⁰ closure 12, shown to be in the nature of an ordinary hinged door, the closure being provided with a lock 13, and is, in addition to being locked, normally sealed. The register may be fastened to the inner side of the door ⁶⁵ or secured separately within the recess; in either case, when in operative position it is arranged to be actuated by a plunger 14 rigid with the press plunger 7, the two plungers being connected together at their upper ends by an intermediate bearing plate ⁷⁰ 15, against which the cam 16 of an operating lever 17 is adapted to bear, both of the plungers being normally retained in their uppermost and retracted positions by a ⁷⁵ spring 18 bearing on the under side of the bearing plate 15 and the bottom wall of a recess 19 formed at the top of the arm 6. Adjacent to the recess 19 the actuating plunger 14 of the register is slidable through an ⁸⁰ opening in the arm 6 leading through the top wall of the recess in which the register is located.

The press is operated in the usual way, as by depressing the operating lever 17 to ⁸⁵ 90 the dotted position shown in Fig. 1, which not only brings the seal dies together to form the impression, but simultaneously therewith by the plunger 14, actuates the register and thus records the impression taken.

With the door leading to the register locked and sealed, it is not possible to gain ⁹⁵ access to the register and tamper therewith without leaving clear traces of the molestation behind, and with the key to the door in the hands of the proper officer, a check can be correctly kept on the number of impressions made with the press.

Having thus described my invention, I ¹⁰⁰ 105 claim as new and desire to secure by Letters Patent:

The combination of a seal press comprising an overhanging arm having relatively long and relatively short parallel bores extending vertically therein, and provided with a cavity between the upper ends of said ¹¹⁰

bores and an enlarged recess below and communicating with the shorter bore, a slideable die plunger mounted in the longer bore, a register actuating plunger slideable in the 5 short bore, a register mounted in said recess and with which said actuating plunger coöperates, a flat cross head connecting the upper ends of the two plungers in spaced relation, a spring seated in said cavity and 10 bearing upwardly against said cross head,

and a lever pivoted in the bore overhanging arm and having a cam for engagement with the upper surface of the said cross head.

In testimony whereof I have signed my name to this specification in the presence 15 of two subscribing witnesses.

CARTER D. STAMPER.
